UNITED STATES PATENT OFFICE.

ADOLPH SCHLUETER, OF OAKLAND, CALIFORNIA.

DISPLAY-STAND AND COIN-HOLDER.

1,349,786.

Specification of Letters Patent. Patented Aug. 17, 1920.

Application filed June 20, 1918. Serial No. 241,032.

To all whom it may concern:

Be it known that I, ADOLPH SCHLUETER, citizen of the United States, residing at Oakland, in the county of Alameda and State of California, have invented certain new and useful Improvements in Display-Stands and Coin-Holders, of which the following is a specification.

This invention is a portable combined display stand and coin holder useful in connection with the sale of articles and commodities by street venders or in stores or the like.

The invention is illustrated in the accompanying drawing which forms a part of this specification and the appended claims.

Referring to the drawing:

Figure 1 is a plan view of the device.

Fig. 2 is a side elevation of one side of the device.

Fig. 3 is a side elevation of the other side of the device.

Fig. 4 is a cross section of the device taken on line 4—4 of Fig. 1.

In the drawing 1 indicates a box-shaped receptacle, the front wall of which is lower than the rear wall and the side walls are inclined at the top, from the top of the front wall to the top of the rear wall. A plate 2 forming the top wall of the box rests upon the top of the front, rear and side walls of the box and is secured thereto by screws 3, the plate inclining downwardly in a forward direction. A pocket 4 is formed in the plate to hold and expose vendable commodities to be sold. A coin receiving pocket 5 is formed in the front part of the plate 2 in which the purchaser deposits his coin for purchasing the articles in pocket 4, which articles the purchaser takes from the pocket.

The coin receiving pocket has a bottom door 6 which entirely closes the pocket in order to prevent the coin or other articles to pass to the interior of the receptacles. The operation of the door is controlled by the clerk or vender by means of a handle 9, the door being mounted on a rod 7 suitably journaled on the bottom of the plate 2 and extending through a side wall of the box 1. A spring 8 normally holds the door 6 closed to hold

the deposited coin in the pocket. The crank 9 is formed on the outer end of rod 7 by

means of which a clerk swings the door 6 open to drop the accumulated coins of several purchases from the pocket into the box 1. Change pockets 10 are formed in the plate 2 forwardly of pocket 4 and rearwardly of coin receiving pocket 5, in which pockets small change, such as pennies, nickels, dimes are placed and exposed so that the purchaser may make change of a coin of higher denomination than the value of his purchase. A guard plate 11 is secured to plate 2 by screws 12 over the pocket 5, forming the top wall of the pocket and is provided with a relatively small opening 13 through which coins are deposited into said pocket. The opening 13 is, however, of such size as would permit the purchaser or vender to insert his fingers in order to recover any coin or article which is accidentally deposited in the pocket 5, it of course being understood that the door or body 6 is normally closed and does not open under the weight of the coin. In the form of the invention herein shown, the top plate or tray 2 is formed of sheet metal and has the pockets 4, 5 and 6 stamped therein. However, any other suitable construction may be employed wherein the suitable pockets will be provided such as shown and described. The box 1 has a side door 14 hinged at 15 which is locked in closed position by lock 16. The clerk from time to time refills the pocket 4 with commodities, and the pockets 10 with coins and delivers the coins from pocket 5 into the box 1.

Having described my invention, I claim as new and desire to secure by Letters Patent:

1. In a device of the character described, a casing having an opening forming a money depository pocket therein communicating with the exterior of the casing, means below said opening for closing the same and controlling the passage of articles from the pocket to the interior of the casing, a guard member covering the pocket and having an opening therein, said opening in the guard permitting recovery of money from the pocket when desired, and means whereby said controlling means may be operated.

2. In a device of the character described, a casing having a tray portion provided with

an opening having inturned flanges forming a money depository pocket and communicating with the interior of the casing, a shutter member arranged below said opening and
5 closing the same for controlling the passage of money into the casing, a guard covering said pocket and having an opening therein,

said opening in the guard permitting the deposit and recovery of money from the pocket, and manually operable means for opening 10 and closing said shutter.

In testimony whereof I affix my signature.

ADOLPH SCHLUETER.
